CLAIM

We claim the ornamental design for a display screen or portion thereof with animated graphical user interface, as shown and described.

DESCRIPTION

FIG. 1 is a front view of a display screen or portion thereof with animated graphical user interface;

FIG. 2 is a front view of the second image thereof;

FIG. 3 is a front view of the third image thereof; and,

FIG. 4 is a front view of the fourth image thereof.

The appearance of the image transitions sequentially between the images shown in FIGS. 1-4. The process or period in which an image transitions to another forms no part of the claimed design. The broken line showing of text and other graphical elements is for the purpose of illustrating portions of the graphical user interface, and forms no part of the claimed design.
